UNITED STATES PATENT OFFICE

RAYFORD RAULERSON, OF DUBUQUE, IOWA

HAT SHAPER

Application filed December 4, 1930. Serial No. 500,054.

This invention relates to wearing apparel and more particularly to a device adapted to be fitted into a hat or cap in order to retain the same in its proper shape.

One object of the invention is to provide a device of this character so constructed that it may be easily applied to a hat or cap and when in place, conform to the contour of the crown portion of a hat or cap and very effectively retain the same in its proper shape.

Another object of the invention is to so form the hat shaper that it may conform to the size of the hat or cap to which it is applied, thereby permitting it to be used in connection with hats or caps of various sizes and shapes and making it unnecessary to supply a series of these devices of different sizes.

Another object of the invention is to provide a device of this character which may be formed principally from a strand of resilient wire bent to assume the desired shape and secured by solder, spot welded or molded in thereby permitting the device to be easily and cheaply made.

The invention is illustrated in the accompanying drawing, wherein:

Fig. 1 is a sectional view showing one of the improved shapers applied to a lady's hat.

Fig. 2 is a perspective view of a man's cap with one of the improved shapers applied thereto and indicated by dotted lines.

Fig. 3 is a top plan view of the improved shaper with the center disc thereof shown in section.

Fig. 4 is a fragmentary sectional view taken along the line 4-4 of Fig. 3.

This improved hat shaper is intended for use either in connection with a lady's hat having a soft crown or a man's cap such as shown in Fig. 2, but it will be understood that it may be applied to other types of hats and caps.

It consists briefly of a series of arms or loops 1 preferably four in number and which radiate from a central mounting 2. These arms or loops are preferably substantially elliptical in shape and formed of thin resilient wire and, therefore, they will be flexible so that they may conform to the shape

of the crown of the hat or cap into which the device is fitted, and also have sufficient resiliency to cause them to be placed under sufficient tension to retain the device in place within the hat or cap and prevent the crown from being dented or otherwise moved out of its proper shape or position.

By referring to Fig. 3 it will be seen that the shaper is formed from a strand of thin resilient wire which is first bent intermediate its ends to form a pair of arms or loops 1, each of which has side portions 3 and 4 joined by a bridge 5. The portions of the wire strand forming the side portions 4 extend in crossed relation to the intermediate portion 6 of the strand and the end portions of the strand are then bent to form a second pair of arms or loops. These arms or loops conform to the shape of the first pair and have side portions 3 and 4 joined at their outer ends by bridge 5. The extreme ends of the wire strand extend in crossed relation to the inner ends of the side portions 4 of the second pair of arms and by referring to Fig. 3, it will be seen that the second pair of arms are joined to the inner ends of the first pair by portions 7 of the strand serving as connecting means. After the wire strand has been bent to assume the desired shape, a mounting disc 8 formed of solder or of any other desired material is applied in order to secure the strand in its bent condition and form a rigid connection or carrier from which the arms project. If the carrier or disc is formed of solder, or an equivalent material, the bent strand will be held in the bent condition and the disc formed by molding. If so desired, the carrier or disc may be formed of companion sections having abutting faces grooved to receive the crossed portions of the strand and any means desired may be employed to secure sections of the disc in engagement with each other. While only four arms or loops have been shown, it will be understood that any number desired may be provided.

When this hat shaper is used, it is grasped by the disc or carrier and thrust into the crown of a hat or cap. A turning motion may be imparted to it as it is fitted into the

hat or cap, thereby causing the arms or loops to move into overlapped relation to each other as shown in Fig. 1, if such positioning of the arms is necessary. In view of the fact that the side portions of the arms are connected by arcuate bridges at their outer ends, these arms will be formed with blunt free ends and there will be no danger of the arms penetrating a hat or cap and also the presence of the shaper within a hat or cap will not be noticed.

The arms may be disposed behind the sweat band 9 of a hat as shown in Fig. 1 or they may terminate above the sweat band. It should also be noted that when a hat is packed for shipment and covered by a sheet of paper in order to protect it from dust, the end portions of the arms will be disposed in front of the sweat band and portions of the protecting paper folded inwardly and engaged by these arms. Therefore, the device will serve as a securing means for the paper as well as a shaper for the hat. The shaper may be applied to a hat while on display in order to keep it in shape when placed on a display rack and removed when the hat is sold or it may be left in the hat and serve as a permanent shaper to prevent the hat from quickly losing its proper shape.

Having thus described the invention, what is claimed is:

1. A hat shaper comprising a central relatively thin flat disk, and a plurality of normally flat resilient loops secured thereto, each loop having anchoring portions embedded in the disk and disposed at substantially right angles to each other, the free ends of the loops being separated and adapted to be flexed downwardly to conform to the shape of the interior of a hat.

2. A hat shaper comprising a central relatively thin flat disk, and a plurality of normally flat resilient loops secured thereto, said loops being provided each with anchoring portions disposed at substantially right angles to each other and embedded in the disk one above and in contact with the other, the free ends of the loops being separated and adapted to be flexed downwardly to conform to the shape of the interior of a hat.

3. A hat shaper comprising a central relatively thin flat disk, and a plurality of normally flat resilient loops secured to and extending laterally from said disk and formed from a single length of wire, the wire at the junction of the loops and disk being bent to form anchoring portions embedded in said disk and disposed at substantially right angles to each other, the free ends of the loops being separated and adapted to be flexed downwardly to conform to the shape of the interior of a hat.

In testimony whereof I affix my signature.
